UNITED STATES PATENT OFFICE.

JAMES L. KEHL AND JOHN GARTHE, OF NORTHPOR, MICHIGAN.

DESIGN FOR A THILL-CO尤LING PLATE.

SPECIFICATION forming part of Design No. 34,719, dated July 2, 1901.

Application filed April 19, 1901. Serial No. 56,887. Term of patent 3½ years.

To all whom it may concern:

Be it known that we, JAMES L. KEHL and JOHN GARTHE, citizens of the United States, and residents of Northport, in the county of Leelanau, State of Michigan, have invented and produced a new and original Design for a Thill-Coupling Plate, of which the following is a full, clear, and exact description.

Reference is to be had to the accompanying drawings, forming a part of this specification, in which similar characters of reference indicate corresponding parts in all the views.

Figure 1 is a plan view of a thill-coupling plate, showing our design. Fig. 2 is a sectional side elevation of the same on the line 2 2 in Fig. 1, and Fig. 3 is a transverse section of the same on the line 3 3 in Fig. 1.

The design in its entirety consists of a forked body A, terminating at its rear end in an axle-plate B, and having the fork members A' of the body A appearing with bayonet-slots A², the vertical members of which lead out through the upper faces of the fork members of the body and into longitudinal slots A³,

appearing in side flanges A⁴, projecting outwardly from the outer faces of the fork members A' flush with the upper faces thereof.

The leading feature of the design consists in the forked body having the bayonet-slots in the fork members and the side flanges extending outwardly from the fork members and flush with the upper faces thereof and appearing with longitudinal slots leading out through the upper faces of the fork members of the body and into the bayonet-slots.

Having thus fully described our invention, we claim as new and desire to secure by Letters Patent—

The design for a thill-coupling plate herein shown and described.

In testimony whereof we have signed our names to this specification in the presence of two subscribing witnesses.

JAMES L. KEHL.
JOHN GARTHE.
